UNITED STATES PATENT OFFICE.

MORTIMER G. MERRITT, OF SPRINGFIELD, MASSACHUSETTS, ASSIGNOR TO
THE MERRITT MANUFACTURING COMPANY, OF SAME PLACE.

TYPE-WRITING MACHINE.

SPECIFICATION forming part of Letters Patent No. 510,985, dated December 19, 1893.

Application filed February 10, 1893. Serial No. 461,754. (No model.)

To all whom it may concern:

Be it known that I, MORTIMER G. MERRITT, a citizen of the United States, residing at Springfield, in the county of Hampden and State of Massachusetts, have invented new and useful Improvements in Type-Writing Machines, of which the following is a specification.

This invention, for improvements in type-writing machines, particularly relates to devices coacting with the platen and its support.

One object of the invention is to provide devices for the machine in which a paper-supply-roll, comprising successive telegraph blanks, or bill or letter heads, may be employed, and in which one, or any multiple of one, rotation of the platen will cause a feed of the paper equal to the distance between the proper severing line of one blank and the severing line of the next,—so that each complete rotation of the platen may be readily determined by the operator, enabling him to tear off the forwardly fed, and then typewritten blank, at the proper place just in advance of the printed heading of the next blank. A severing device in this class of machines may usually consist in the serrated plate or a blade on the platen support just in front of the platen. An advantageous result incidental to the mechanism consists in such a checking of the movement of the platen imparted by the platen-rotating-mechanism, as to prevent any by-throw of the platen which would cause too wide or irregular line-spacing; and another result consists in the indication by the position of certain notches on the platen, of the proper position of the blank relative to the typewriting impact line at the under side of the platen to enable the operator to determine that he is imprinting upon the open space of the blank and not upon the printed heading.

Another object of the invention is to so support the platen on the carriage that the platen may be swung up to show the last line or lines of typewriting without upswinging the carriage, and so that, at will, the act of upswinging the platen will also swing up the carriage, as may be desirable for gaining access to the type for cleansing them or for other purposes.

To these ends the invention consists in the constructions and combinations of parts all substantially as will hereinafter fully appear and be set forth in the claims.

Reference is to be had to the accompanying drawings in which—

Figure 1 is a perspective view of the carriage, the platen support or frame, the platen, and the present novel devices applied in relation thereto. Fig. 2 is a view taken at the right hand end, showing the platen-frame and platen and the parts for attaining the first named object of the invention, applied thereto. Fig. 3 is in part a section and in part 65 an elevation for clearly showing the catch device for the platen. Fig. 4 is a vertical sectional view through the extremity of one of the arms on which the paper-supply-roll is hung. Fig. 5 is a view in detail illustrating 70 a slight modification. Fig. 6 is a view illustrating a notched formation at the end of the platen, hereinafter referred to.

In the drawings, A represents the carriage which is movable along the front and rear slide-rails, *a* and *b*, in the manner usual in typewriting machines. The engagement between the carriage, A, and its rear slide support, *a*, is such that the carriage may be upwardly and rearwardly swung, as usual.

B represents the frame, or support, in which the platen, C, is mounted for its rotation. This frame has a pivotal engagement at each end through the stud, *d*, with the hooked or socketed part, *f*, at each end of the carriage, all as is common in the well-known Densmore typewriting machine; and thus, again, the carriage, with the platen, may be rearwardly and upwardly swung, or the platen-frame may be swung on the connection at *d*, *f*, independently of the carriage.

D represents a catch for uniting the carriage and platen so that while said catch remains in its uniting engagement between said parts, when the platen-frame is then swung the carriage must also be swung in unison therewith. This catch device, as shown, consists of an angular lever pivoted, at its elbow, on the platen-frame and having its depending arm, *l*, hooked to engage a suitably formed 95 part of the forward member, *g*, of the carriage. The forwardly extended arm, *h*, of

the lever projects above the rigid forward extension, *i*, of the platen-frame, and the spring, *j*, is applied to maintain the engagement between the catch-lever and carriage.

- 5 The operator, on desiring to merely swing up the platen and its frame, grasps, as manifestly most natural, both the projection, *i*, and arm, *j*, between the thumb and finger, effecting the release of the catch; on desiring to swing 10 up the carriage a lifting force is only imparted to the projection, *i*. The platen has at its end the regular series of ratchet-teeth, 10, with which the impelling pawl, 12,—carried on the pawl-carrier, 13,—has engagement. 15 The pawl-carrier is actuated by the lever, 14, which is pivoted on the platen-frame, and the pawl, pawl-carrier, and lever, 12, 13, and 14, are all retracted by the spring 15. Other platen rotating devices may, of 20 course, be substituted.

Referring now to the platen engaging device, it will be perceived that the platen has at its end, or on a part which is secured thereto at its end, a formation to constitute a catch-engagement-portion, and which, as shown, 25 consists of a deep notch, *m*; a pawl, *n*, which, as shown, is in the form of a lever pivoted on a rear proximate portion of the platen-frame and formed with a nose, *n'*, normally bears peripherally on the circular portion of, or attached to, the platen which has the aforesaid deep-notch. Each time the platen is 30 completely rotated by the lever and pawl mechanism described, the pawl-lever, *n*, will swing into a somewhat forcible engagement within the said notch, as impelled by the pawl-spring, *o*. Now the amount of force habitually applied on the lever, 14, for line spacing, will be 35 insufficient to effect the further rotation of the platen, and the operator will become aware that the blank has been fed sufficiently far to be severed across the serrated blade, *x*, should he not have already become so warned, by the 40 clicking of the pawl, *n*, into the deep-notch. 45 The continued rotation of the platen may be insured for bringing forward the next blank by giving a more forcible impetus to the lever, 14, when the inclined edge of the deep notch will force itself past the nose of the impeding 50 pawl, *n*, causing the latter to resume its position of rest upon the periphery of the circular part, within which the notch is formed. The catch devices last referred to need not necessarily consist of a notch in the circular part 55 of or for the platen, as in lieu thereof the projection, *m'*, may be provided, as seen in Fig. 5, with which a depression in the pawl-lever may come to engagement. This reversal, or 60 inversion, is merely an obvious mechanical substitute for the device for the same purpose, described in connection with Fig. 3. The pawl, *n*, has the stud, *p*, thereon, with which 65 may engage the cam-inclined end of the lever, *q*, which lever is pivoted on the arm, *t*, of the platen-frame. By swinging this lever, *q*, forwardly, the pawl is forced and maintained out of operative engagement with the end of the

platen, as desirable for ordinary use of the typewriting machine, that is, when no particular heed need be paid to the feed across the 70 platen of the paper.

On the part at the end of the platen which has the catch engagement portion, *m*, there are shallow notches, *u*, *u*, corresponding in separation to the distance between the ratchet- 75 notches, 10, 10, and with which the nose of the pawl, *n*, may have a clicking engagement. These notches, *u*, *u*, are comprised in a circumferential portion of the circular part borne upon by the pawl, *n*, proportionate to the 80 whole of such circumference as the open space of the blank, on which the typewriting may be imprinted, is to the length of the blank, and the length of the blank usually corresponds to the distance which the platen will 85 feed the paper on one complete rotation thereof.

Having once properly entered the paper between the usual spring-fingers and the platen, and brought the end of the paper to 90 coincidence with the severing blade, with the printed heading toward the latter, the operator may now be aware that while running the machine so long as any of the notches, *u*, are in sight in advance of the 95 pawl, *n*, he is imprinting on the blank within the proper space below the heading; either on the date line or therebelow. The nose of the pawl also takes into these notches as the paper is forwardly fed to prevent by- 100 throw of the platen in case of too impetuous swinging of the lever, 14. Should the operator finish the message, &c., more or less above the place for the last line on the blank, and draw the paper forward by grasping it with 105 the fingers, he may continue to so draw the paper until it has been brought with its severing line to the severing blade, at which time the pawl, *n*, entering the deep notch, *m*, will cause a resistance to the further rotation 110 of the platen greater than may be overcome by any draft tension which may be withstood by the paper without its tearing.

It is understood that the roll of paper is upon a core, and that the latter is centered 115 on the conical extremities of the studs which are supported in axial alignment by the arms, *t*, *w*, of the platen-frame. One of the centering studs, as seen in Fig. 4, is movable against 120 an inclosed spring for the engagement or disengagement of the roll from its support.

Having thus described my invention, what I claim, and desire to secure by Letters Patent, is—

1. In a typewriting machine, the combination of the roller platen with a platen-support, and a support for a paper-supply-roll, and a device for rotating the platen, and a catch, supported adjacent the platen, to automatically engage and impede the platen on 125 each complete rotation thereof, substantially as described.

2. In a typewriting machine, the combination of the roller platen having its end por-

tion formed to receive the engagement therewith of a catch, with the platen-support, and a support for a paper-supply-roll, and a device for rotating the platen, and a catch, supported adjacent the platen, to engage the aforementioned portion of the latter on each complete rotation of the platen, and a device supported relative to the platen catch for throwing the latter into an inoperative position, substantially as described.

3. In a typewriting machine, the combination with a platen support and platen rotatably mounted thereon having a notch formed in its peripheral portion near its end, and a device for rotating the platen, of a spring-forced lever pivoted adjacent the peripheral end portion of the platen and having a nose or tooth to bear thereagainst and on each complete rotation of the platen to enter the aforesaid notch, substantially as described.

4. In a typewriting machine, the combination with the platen having the catch portion, and the ratchet teeth, of the platen-frame having the arms, *t*, *w*, at its ends, between which the paper-supply-roll is hung and the severing plate or blade at the front of the platen support, the catch lever pivoted to one of the said arms and having the spring, *o*, applied thereto and the pawl device for rotating the platen, substantially as described.

5. In a typewriting machine, the combination with the roller platen having ratchet-teeth or notches and having a circular portion provided, through a portion only of its peripheral extent, with a series of slight depressions at intervals corresponding to the spacing of the aforesaid ratchet-notches and

having the deep notches, *m*, of a platen support, a support for a paper roll, and an actuating pawl for engaging the notches of the platen, and the pawl, *n*, substantially as and for the purposes set forth.

6. In a typewriting machine, the combination with the carriage and the support on which it slides and relative to which it has its up-swinging movement, of the platen-frame pivotally engaged with the carriage for its up-swinging movement relative thereto, and independently thereof, and having the arm or projection, *i*, the elbow-lever pivoted on the platen-frame having the hooked arm, *l*, to engage the carriage, and the arm, *h*, extended forwardly over the said projection of the frame, and a spring, *j*, for the elbow-lever, all substantially as described. 55

7. In a typewriting machine the combination with a roller platen, and a platen catch device, to automatically engage and impede the platen on each complete rotation thereof of a shift device for throwing the platen catch into an inoperative position, substantially as described.

8. In a machine designed for typewriting on printed blanks, a severing device near the platen, and the platen having indications thereon arranged in such a fractional part of a circle as corresponds to the fraction which the open space on the blank to be used in the machine bears to the normal length of the blank, substantially as described. 65
